Patented Dec. 22, 1970

219,566

SMOKING PIPE STEM

Paul Fish, Winston-Salem, N.C., assignor to Henry Leonard & Thomas, Inc., Winston-Salem, N.C., a corporation of New York

Filed Dec. 30, 1969, Ser. No. 20,707

Term of patent 14 years

Int. Cl. D27—02

U.S. Cl. D85—8

FIG. 1

FIG. 5

FIG. 6

FIG. 2

FIG. 3

FIG. 4

FIG. 1 is a perspective view of a smoking pipe embodying my new design;

FIG. 2 is a side elevational view on a reduced scale, the opposite side being a mirror image of the side shown;

FIG. 3 is a bottom plan view;

FIG. 4 is a top plan view;

FIG. 5 is an elevational view looking from the left of FIG. 2; and

FIG. 6 is an elevational view looking from the right of FIG. 2.

I claim:

The ornamental design for a smoking pipe stem, as shown and described.
